By Robert S. Carr, Attorney.

UNITED STATES PATENT OFFICE.

JOSEPH J. PAYNE, OF CINCINNATI, OHIO.

CARBURETER.

1,148,333.

Specification of Letters Patent. Patented July 27, 1915.

Application filed February 4, 1915. Serial No. 6,165.

To all whom it may concern:

Be it known that I, JOSEPH J. PAYNE, a citizen of the United States, residing at Cincinnati, Ohio, have invented a new and useful Improvement in Carbureters, of which the following is a specification.

My invention relates to carbureters of the class adapted to the use of motor vehicles or for other suitable purposes, and the objects of my improvements are to provide positive means for controlling the volume of air admitted to the mixing chamber in relation to the volume of gas admitted thereto for maintaining the desired proportion of the fuel mixture under different demands for quantity; to provide means for controlling the quantity of the fuel mixture to be admitted to the explosion chamber of the engine under different speeds and duties without changing its quality; to provide means for admitting the air to the mixing chamber from opposite directions to a common meeting point and perpendicular to the movement of the gas thereto for effecting a more thorough mixture of the fuel ingredients, and to provide simple and durable construction and assemblage of the various members for securing facility of operation and efficiency of action. These objects may be attained in the following described manner, as illustrated in the accompanying drawings, in which:—

Figure 1 is a diametrical section with broken parts in elevation of a carbureter embodying my improvements; Fig. 2 a transverse section on the line $a-a$ of Fig. 1 and Fig. 3 a front elevation with parts broken away.

In the drawings, 1 represents the tubular body of the carbureter and 2 the tubular mixing chamber integral therewith, and extending perpendicular therefrom in opposite directions. Said body terminates at its top in an enlarged opening 3 adapted to communicate with the vacuum chamber of an explosive engine, and at its bottom in the hollow stem 4 whereon the float chamber 5 may be swiveled by means of the movable engagement of the pin 6 with the annular groove 7 formed in the stem. Said float chamber is of the ordinary construction and operation and is provided with the gasoline jet nozzle 8 to discharge within the hollow stem in the usual manner. A rotatively adjustable gate 9 serves to control the air in-

let opening 11 formed in the tubular shank 12 of the float chamber in the usual manner.

The mixing chamber 2 which intersects the body is formed with open ends and with similar open slots 13 in its end portions, as shown in Fig. 1. Cylindrical caps 14 are rotatively adjustable on the said respective end portions of the mixing chamber and each of them is formed with similar longitudinal slots 15 adapted to register with the corresponding slots 13 in the end walls of the mixing chamber. Each of said caps may be formed with a slotted radially projecting arm 16 adapted to movably engage with the corresponding ends of the double crank shaft 17 which may be journaled in bearings 18 secured on the body and parallel with the mixing chamber as shown in Fig. 3. Said shaft is provided with an arm 19 whereby it may be adjusted with the caps simultaneously to laterally control the width of the slots 13 for admitting more or less air to the interior of the mixing chamber in proportion to the amount of gasoline admitted thereto from the jet nozzle 8.

A tubular gate valve 21 is slidable longitudinally within the cylindrical mixing chamber by means of the rod 22, and is formed with an open end 23 and near its opposite end with longitudinal slots 24 adapted to register with the corresponding slots 13 in the wall of the mixing chamber. Said valve is also formed with a longitudinal opening 25 for the free passage therethrough at all times of the carbureted air from the jet nozzle to the interior of said valve and also with a circular opening 26 to admit more or less of the fuel mixture therefrom to the discharge opening of the body. The longitudinal movement of said valve is limited and its rotative movement prevented by means of the movable engagement of the fixed pin 27 with the longitudinal slot 28 formed in its side wall.

Separate actuating connections (not shown) and placed conveniently accessible to the operator may be made with the gate valve, the crank shaft and with the adjustable gate 9.

In operation, the rotative adjustment of the caps may serve to control the width of the air inlet slots 13 formed through the wall of the mixing chamber for controlling the proportion of air in relation to the amount of carbureted air to said chamber for changing the quality of the fuel mix-

ture. The longitudinal movement of the gate valve serves to more or less open the slots 13 longitudinally and simultaneously to more or less open the passage through 5 the opening 26 for providing and admitting more or less of the fuel mixture to enter the discharge passage to the engine.

Spring actuated automatic controllers for regulating the relative proportion of the air 10 to the carbureted air in the mixing chamber are limited in their range and efficiency.

To those skilled in the art the many advantages is evident of accessible facilities arranged for separately and positively controlling the quality and also the quantity 15 of the fuel mixture to meet the requirements of different speeds and also more or less heavy duty required of the engine.

Having fully described my improvements, 20 what I claim as my invention and desire to secure by Letters Patent of the United States is:—

1. In a carbureter, the combination of a tubular body formed with a transverse mixing chamber having slotted end portions, 25 similarly slotted caps rotatively adjustable on said end portions for changing the width of the slots therein, a gate valve movable longitudinally within the chamber for controlling the discharge opening therefrom and for simultaneously changing the length 30 of the slotted openings, separate actuating connections with the valve and with the caps, and a float chamber provided with a 35 gasolene nozzle terminating within the body beneath the chamber.

2. A carbureter comprising a tubular body formed with a tubular mixing chamber perpendicular thereto terminating in a 40 series of longitudinal slots, a correspondingly slotted cap rotatively adjustable thereon and arranged to adjust the width of said slots, a gate valve for the body movable longitudinally within the chamber for 45 changing the length of said slots, separate actuating connections therewith and with the cap, and a gasolene nozzle terminating within the body beneath the chamber.

3. A carbureter comprising a tubular body, a tubular mixing chamber formed 50 transversely thereon and terminating in a series of longitudinal slots at one end and being formed with a similar series of slots near its other end, similarly slotted caps rotatively adjustable thereon for changing the 55 width of said slots, a tubular gate valve for the body and movable longitudinally within the chamber for simultaneously changing the length of the slots therein, a float chamber provided with a gasolene nozzle arranged to discharge within the body beneath the mixing chamber, and separate 60 actuating connections with the valve and with the caps.

4. In a carbureter the combination with a tubular body, a float chamber swiveled thereon and provided with a gasolene nozzle arranged to discharge therein, of a tubular mixing chamber formed transversely on said body above the nozzle and formed with air 65 inlet slots in its opposite end portions, a tubular gate valve for the body slidably mounted within the chamber and arranged to control the length of the slots therein, independent means for simultaneously adjusting 70 the width of said slots, and separate actuating connections therewith and with the said valve.

5. In a carbureter, the combination with a tubular body, a transverse mixing chamber integral therewith and formed with longitudinal slots in its end portions, a gasolene nozzle arranged to discharge within the body beneath the chamber, and means 80 for simultaneously adjusting the width of the slots, of a tubular gate valve for the body and slidably mounted within the chamber, said valve being arranged to simultaneously control the passage through the body and also the length of the slots, and 85 actuating connections therewith.

J. J. PAYNE.
